[57] CLAIM

The ornamental design for a mop bucket, as shown and described.

DESCRIPTION

FIG. 1 is a top front perspective view of a mop bucket embodying our new design.

FIG. 2 is a vertical section on line 2—2 of FIG. 5.

FIG. 3 is a side elevational view of the side opposite to that shown in FIG. 1.

FIG. 4 is a rear elevational view thereof.

FIG. 5 is a top plan view thereof.

FIG. 6 is a bottom plan view.

The side opposite to that shown in FIG. 3 is a mirror image thereof.

FIG. 1

FIG. 2

FIG. 3

FIG. 4

FIG. 5
